SUBMERGED WATER HEATING COIL

Victor Feldman, New York, N. Y.

Application June 26, 1935, Serial No. 28,405

3 Claims. (Cl. 122—32)

This invention relates to new and useful improvements in a submerged water heater.

The invention has for an object the construction of a submerged water heater which is characterized by a boiler having a longitudinal water compartment through which the fire tubes extend longitudinally, and water heating tubes mounted on one side of the boiler and extending into the water space obliquely of the side walls of the boiler and upwardly inclined with respect to the horizontal. The advantage of this construction will become readily apparent by considering prior devices.

It has been customary to construct submerged water heaters which are extended in from the front of a boiler. This is a very efficient type since the water tubes may then extend the full length of the water compartment of the boiler. However, very often it cannot be installed as an attachment on boilers as the fronts have no spare space which may be utilized. Consequently, numerous other types of submerged water heaters have been constructed to be used in various ways.

A generally used type of submerged water heater is one in which an auxiliary tank is mounted adjacent the boiler and the water from the boiler connected with the tank. The water heating tubes are then mounted within the water of the tank. This method is undesirable for several reasons, namely, it requires an auxiliary tank and the circulation between the water in the tank and the boiler being poor. Some installations therefore utilize a circulating system which adds to the expense.

Another type of submerged boiler is the arrangement of an auxiliary hollow member which is attached on the side of the boiler and lengthens the operative width of the boiler at this area. It is then possible to insert the water heating tubes in this auxiliary member and into the boiler.

If the tubes were inserted transversely into the boiler without the auxiliary member, there would not be sufficient heating area of the tubes to operate properly. The disadvantage of this type of water heater resides in the fact that the hollow member which is attached on the side is unsightly and quite large, and very often the location of the boiler is such that there is no room for the member.

It is applicant's concept to engage the heating tubes into the side of the boiler, but obliquely and upwardly inclined with respect to the horizontal, so that they are comparatively long and at the same time all need of an auxiliary tank or projecting extension member has been eliminated.

Another object of the invention is the construction of a device as described which is simple and durable and which may be manufactured and sold at a reasonable cost.

For further comprehension of the invention and of the objects and advantages thereof, reference will be had to the following description and accompanying drawing, and to the appended claims in which the various novel features of the invention are more particularly set forth.

In the accompanying drawing forming a material part of this disclosure:—

Fig. 1 is a perspective view of a boiler with a submerged water heater constructed according to this invention.

Fig. 2 is a side elevational view of the water heater, per se.

Fig. 3 is an edge elevational view of Fig. 2 looking in the direction of the line 3—3 of Fig. 2.

Fig. 4 is an end elevational view looking in the direction of the line 4—4 of Fig. 2.

Fig. 5 is a sectional view taken on the line 5—5 of Fig. 2.

Fig. 6 is a fragmentary plan view of a portion of Fig. 1.

Fig. 7 is a view similar to Fig. 6 but illustrating another embodiment of the invention.

The submerged water heater, according to this invention, is used in combination with a conventional boiler 10 which has a longitudinal water compartment 11 in which the fire tubes 12 extend longitudinally. The submerged water heater comprises water heating bent tubes 13 mounted through the side of the boiler and extending into the water space obliquely of the side wall and upwardly inclined with respect to the horizontal. To facilitate the mounting and installation of the water tubes, a water inlet and outlet member 14 and support 14' therefore is secured in an opening formed in the side of the boiler. This water inlet and outlet member has an inlet 14a terminating in a plurality of small openings 15 in which one of the ends 13a of one group of the tubes 13 engage. The other ends 13b of this group of tubes 13 connect with certain openings 14b in a central compartment 14c in the member 14. Another group of tubes 13 have their ends 13c connecting with the remainder of the openings 14b. The other ends of the tubes 13 of this group connect with other openings 14d in the outlet portion 14e of the member 14. The construction is such that water enters the inlet 14a, circulates through one group of the tubes 13, then circulates through the compartment 14c, through the other groups of tubes 13, and finally discharges from the outlet 14e.

The member 14 is attached upon a support member 14' by several bolts 16 which engage through lugs 17 on flanges of these parts. The member 14' is tubular and engaged into an opening 18 in a side wall of the furnace, and is welded in position to make a waterproof joint.

In Fig. 7 another embodiment of the invention has been disclosed which is very similar to the prior form except for the fact that there is a support member 14'' upon which the water inlet and outlet member 14 is mounted. This member 14'' is solid (not tubular) except for the fact that it is formed with a plurality of passages 14^z. The tubes 13 are connected directly with the inner ends of these passages. The support member 14'' also has passages 14^z connecting with the compartment 14^c. The object of this construction is to eliminate the extension of the tubes 13 into the hollow of the member 14'. The advantage gained is that the construction will be much stronger in that the projecting part from the boiler is solid instead of hollow. The support member 14'' has a base flange 14^x which is welded on the side of the boiler over the opening 18. Several studs 14^y are mounted on the flange 14^x and pass through flanges upon the outer end of the support member 14'' and the member 14. Nuts 14^w are mounted upon the studs 14^y and serve to hold the member 14 in position.

The operation of the device is very similar to prior submerged water heaters, except for the fact that because the tubes 13 are arranged obliquely and upwardly inclined with respect to the horizontal, they may be relatively long, much longer than the width of the boiler though not as long as the length of the boiler, and at the same time they are mounted upon the side of the boiler.

By having the tubes inclined upwardly with respect to the horizontal plane of the boiler so that they pass above the fire tubes, additional length is achieved over tubes parallel to the horizontal plane.

While I have illustrated and described the

preferred embodiment of my invention, it is to be understood that I do not limit myself to the precise construction herein disclosed and the right is reserved to all changes and modifications coming within the scope of the invention as defined in the appended claims.

Having thus described my invention, what I claim as new, and desire to secure by United States Letters Patent is:—

1. In combination, a boiler having a longitudinal water compartment through which fire tubes extend longitudinally, a water inlet and outlet member mounted obliquely upon and extended obliquely through an opening in one of said side walls, and water heating tubes mounted on said member and connected with said inlet and outlet and extending into said water space obliquely to said side wall and upwardly inclined with respect to the horizontal.

2. In combination, a boiler having a longitudinal water compartment through which fire tubes extend longitudinally, a water inlet and outlet member mounted on and extending obliquely through an opening in one of said side walls, and water heating tubes mounted on said member and connected with said inlet and outlet and extending into said water space obliquely to said side wall and upwardly inclined with respect to the horizontal.

3. In combination, a boiler having a longitudinal water compartment through which fire tubes extend longitudinally, a water inlet and outlet member mounted obliquely upon and extended obliquely through an opening in one of said side walls, and water heating tubes mounted on said member and connected with said inlet and outlet and extending into said water space obliquely to said side wall and upwardly inclined with respect to the horizontal, said member being supported on a tubular member welded upon the side of the boiler and in an opening in the side wall.

VICTOR FELDMAN.
